United States Patent Office

Des. 211,382
Patented June 11, 1968

211,382

CREAMER OR THE LIKE

Rudolph Erenhouse, 849 Barth Drive,
Baldwin, N.Y. 11510

Filed Aug. 18, 1966, Ser. No. 3,519

Term of patent 14 years

(Cl. D44—21)

FIG. 1

FIG. 2

FIG. 3

FIG. 1 is a perspective view showing a creamer embodying my design;

FIG. 2 is a top plan view of the creamer of FIG. 1; and

FIG. 3 is a front view of the creamer of FIG. 1.

I claim:

The ornamental design for a creamer or the like, substantially as shown and described.
